United States Patent

Des. 241,012

Patented Aug. 17, 1976

241,012

BOTTLE

Joaquin de Muller y de Abadal, Rambla Generalísimo 38,
Tarragona, Spain

Filed June 21, 1974, Ser. No. 481,709

Claims priority, application Spain Apr. 2, 1974

Term of patent 14 years

Int. Cl. D9—01

U.S. Cl. D9—151

FIG. 1

FIG. 2

FIG. 3

FIG. 1 is a front elevation of a bottle showing my new design;

FIG. 2 is a top plan view; and

FIG. 3 is a bottom plan view thereof.

The side of the bottle not shown is substantially the same in appearance as the side shown.

I claim:

The ornamental design for a bottle, as shown and described.
